UNITED STATES PATENT OFFICE.

ANDREW RYDER, OF OAKLAND, CALIFORNIA.

APPARATUS FOR TREATING ORES.

SPECIFICATION forming part of Letters Patent No. 239,300, dated March 22, 1881.

Application filed July 3, 1879.

To all whom it may concern:

Be it known that I, ANDREW RYDER, of Oakland, Alameda county, State of California, have invented an Improvement in Apparatus for Treating Ores; and I do hereby declare that the following is a full, clear, and exact description of the invention.

My invention has reference to apparatus for reducing ores in which the ore, while in a heated state, is dumped suddenly into a liquid or chemical solution for the purpose of disintegrating the ore and separating the particles preparatory to amalgamation.

In operating this apparatus the ore is first heated in such ordinary-sized particles as are easily handled without subjecting it to any crushing or pulverizing action. When it is thoroughly heated through it is dumped suddenly into a liquid bath, either of water or some chemical solution, which causes it to disintegrate, or, rather, to be reduced to a friable condition, so that it can be easily crushed and the particles separated from each other. This method of treating ores was first described and claimed by Dr. J. C. Ayer in his Letters Patents No. 46,619, 46,620, and 46,621, dated March 7, 1865.

My invention consists of an apparatus for charging the liquid or solution with electricity while the ore is being subjected to this bath treatment, so that as soon as the disintegration consequent on plunging the heated ore into the bath takes place each metallic particle will be subjected to the action of the electric currents, which will strip it of any surrounding envelope or coating that would otherwise prevent amalgamation.

It is well known that the sudden immersion of heated ore in a liquid bath or solution generates electricity; but the quantity is not usually sufficient to produce the required energy; and, even if it were sufficient in quantity, no means have ever been devised for retaining the electricity in the vessel under such circumstances. The vessel in which the liquid or solution is contained is generally made of metal, and connected with the ground so that the electricity passes off into the earth before any benefit can be derived from it. To utilize this electricity, I insulate the tank or vessel from the earth if it is made of metal; or I can use tanks or vessels made of some non-conducting substance or material.

My invention therefore consists in subjecting the ore, while in a heated state, to the com-

bined action of a liquid bath and electricity, whether the electricity be generated in the liquid or solution by the immersion of the ore or generated outside the tank and introduced through conductors.

60

Referring to the accompanying drawings, Figure 1 is a view of my apparatus in side elevation, and Fig. 2 is a vertical section of the same.

Let A represent the tank or vessel in which the cold liquid or solution is contained. If this tank or vessel is made of metal, and if I intend to depend only on the electricity generated by the immersion of the heated ore in the liquid or solution, I mount it upon a frame or platform, B, that is made of a non-conducting substance or material, great care being taken that no metallic conductors connect it with the earth. I then dump the heated ore in the liquid or solution, and the electricity is retained in the vessel; but a tank made of earthenware, wood, or other non-conducting material can be used. If I wish to produce a more energetic electric action than the submersion of the ore in the liquid or solution produces, I use a galvanic battery or dynamo-electric generator, C, and lead the two wires d e into the solution and connect them with copper plates f f, which are so placed that the ore, in descending through the liquid or solution, will be compelled to pass between the edges of the plates. During this passage of the particles between the edges of the plates they will be shocked by the electric current. This will separate the metallic particles from the gangue and strip them of any casing or envelope that may surround them, so that they will amalgamate readily when brought in contact with mercury.

Having thus described my invention, what I claim, and desire to secure by Letters Patent, is—

In an apparatus for disintegrating ores preparatory to amalgamation, the insulated vessel or non-conductor of electricity, provided with a metallic or plated hopper, in combination with an electrical generator or battery and conducting wire or wires, substantially as and for the purpose set forth.

In witness whereof I have hereunto set my hand and seal.

ANDREW RYDER. [L. S.]
